UNITED STATES PATENT OFFICE.

CHARLES R. WYBORNEY, OF WILBUR, WASHINGTON.

FEATHERING PADDLE WHEEL.

Application filed June 22, 1926. Serial No. 117,719.

This invention relates to feathering paddle wheels, and belongs to that class or type of revolving devices provided with adjustable paddles or blades and immersed at the sides or stern of a boat, which permit the motor to run continuously in the same direction while the adjustment of the paddles enables the operator to move the boat forward or backward and to steer the same without the employment of the usual rudder. Such wheels may be arranged either with the propeller shaft vertical or horizontal.

The object of this invention is the production of an apparatus of the class mentioned having special construction and arrangement of the parts, whereby it is believed a strong, simple and durable boat driving mechanism is made which does not require one person to attend to the motor and another to pilot the boat. The motor may run constantly without particular attention, while the operator is occupied solely with the speed and direction of the vessel.

In the accompanying drawings the preferred form of this invention is illustrated, and Figure 1 represents a side view of a boat having this invention applied thereto, and showing all the parts assembled.

Figure 2 is a side view of a paddle wheel constructed in accordance with this invention, and showing the arrangement of the paddles in one of the positions when driving the boat forward.

Figure 3 is a side view similar to the second figure and showing the arrangement of the paddles in one of the positions when driving the boat backward.

Figure 4 is a vertical section of a paddle wheel made in accordance with this invention, and showing the means for adjusting and holding the central or master gear wheel of the planetary gearing employed.

Throughout the description and drawings the same number is used to refer to the same part.

Considering the drawings, a boat 1 has at the stern a suitably supported paddle wheel shaft 2, driven by a motor 3, motor shaft 4 and bevel gearing 5 and 6 to the paddle wheel shaft. This invention is not limited to the driving means illustrated or to the position of the paddle wheel as shown. The wheel is drawn vertical in position but may as well be placed horizontally. Furthermore, it is believed to be within the purview of this invention to employ two wheels side

by side driven by the same motor and provided individually or in common with means for altering the inclination of each paddle as described herein.

Each paddle is provided with a revolving gear 7 in mesh with an intermediate gear 8, which in its turn is engaged by a central or master gear 9. The gearing for each paddle is the same and an explanation of one set will describe each of the other sets. The central gear 9 is fixed upon a sleeve shaft 10 through which the paddle wheel shaft 2 passes as delineated in Figure 4. At any convenient point the sleeve 10 is provided with a worm 11 on the vertical shaft 12, and at its upper end the shaft 12 has the mitre gear 13 engaging a like gear 14 on a horizontal operating shaft 15 turned by a handle 16, or equivalent means.

In the operation of this invention, it will be noted that the worm adjustment for the central gear is equally a means for holding that gear after it has been adjusted, and it is not displaced by the paddle gearing mentioned. The gearing is proportioned to revolve each paddle once with each revolution of the wheel as a whole. Let it be assumed that the paddle gear 7 rotates the paddle 17 which is pivotally attached in revolute relation to a support 18 forming as illustrated one side of the wheel of which the other side is usually a similar member marked 19. If the central gear is so adjusted as to bring the paddles into the positions set out in Figure 2, the paddle 17 will be horizontal and in line with the movement of the boat when it is uppermost, and perpendicular to the direction of movement of the boat when it is in its lowest position. In the intermediate positions the paddle is inclined in opposite directions with respect to the line of movement of the boat. These various positions are brought about by the fact that the paddle rotates upon its own axis and is at the same time carried around by the rotation of the wheel as a whole. The wheel as set out in Figure 2 turns in the direction of the arrow, and it will be noted that each paddle throws the water rearwardly through more than one-half of the rotation of the wheel as a whole. It will be further observed that the ratio of the paddle gear 7 and intermediate gear 8 is two to one, and while the gear 8 turns one-fourth around, the gear 7 turns but one-eighth of a full rotation to cause the paddle

to take up the position of inclination on the right of Figure 2. It is thought to be clear from the foregoing and the drawings that when the center gear is adjusted by the worm to cause the paddles to assume the various positions indicated in Figure 3, the wheel being wholly submerged, the water will be thrown forward and the boat moved aft.

10 As previously stated, paddle wheels made in accordance with this invention may be located in pairs at the stern or amidships at the side, and in the manner well understood if the paddles of one wheel are caused to assume the positions illustrated in Figure 2 while the paddles of the second wheel take up the attitudes set out in Figure 3, the hull will be turned without the necessity for a rudder and its operating members. As the 15 motor always runs in one direction when this invention is used, the attention of the operator may be devoted solely to directing the course of the boat.

Having now described this invention and explained the mode of its operation, what I claim is:—

A submerged feathering paddle wheel comprising a revolvably mounted wheel sup-

porting shaft, a pair of spaced, parallel paddle supporting plates concentrically arranged with respect to and fixedly mounted on said shaft, a plurality of transverse paddle shafts revolvably mounted equi-distances apart in said supporting plates and concentrically arranged with respect to said main shaft, paddles fixed on said shafts between said plates, gears fixed on one end of said paddle shafts adjacent to the outer side of one of said supporting plates, a drive shaft 30 geared to said wheel supporting shaft whereby said paddle supporting plates are revolved, a sleeve loosely mounted on said wheel supporting shaft, a pinion fixed on one end of said sleeve, a plurality of intermediate gears mounted on one of said supporting plates and connecting said pinion with the gears on said paddle shafts, a shaft 35 having a worm gear connection with said sleeve whereby the latter and said pinion are turned and the paddles thereby adjusted through the medium of said intermediate gears and paddle shaft gears, and a hand operated shaft geared to said worm gear shaft for turning the latter and said sleeve.

In testimony whereof I affix my signature.

CHARLES R. WYBORNEY.
